RADIO RECEIVING APPARATUS

Alfred H. Grebe, Hollis, N. Y.

Application June 3, 1931. Serial No. 541,929

7 Claims. (Cl. 178—44)

This invention has to do with improvements in radio receivers, specifically it relates to an improved circuit arrangement whereby the resonance characteristics of the tuned circuits of the intermediate frequency amplifier of a superheterodyne receiver may be changed, easily and by a definite amount, at the wish of the operator.

Several circuit arrangements suitable for carrying my invention into effect, are illustrated in the accompanying drawings, but I do not wish to be understood as intending to limit myself to the exact details shown, as various changes may be made therein within the meaning of the present invention, as set forth in the appended claims.

In the drawing, Figure 1 shows the normal assembly of a superheterodyne receiver; Figure 2 shows a circuit detail of one stage of the intermediate frequency amplifier, Figure 3 shows a circuit detail of part of the intermediate frequency amplifier equipped with my resonance changing arrangement. Figure 4 shows the difference selectivity characteristics of the circuit, as obtainable with my invention. Figure 5 shows a possible modification of the scheme of Figure 3. Figure 6 shows a further modification of my tuning arrangement.

Referring to Figure 1, A is the tuned input circuit of the superheterodyne receiver and B is the local oscillator. The combined action of the local oscillator B and the tuned receiving circuit A is to produce a signal modulated wave having a frequency much lower than that of the incoming signal. This lowered frequency (called the intermediate frequency) is supplied to the intermediate frequency amplifier C, (hereafter abbreviated I F A). From the amplifier, the signal ordinarily is supplied to an audio frequency amplifier D and thence to the loud speaker E.

My invention has to do specifically with an improved circuit arrangement for the I F A and to understand and appreciate its operation and advantages, it is necessary that the action of the I F A be made clear. A part of the circuit of the I F A is shown in Fig. 2.

The signal modulated intermediate frequency current is supplied to the input circuit of the vacuum tube T₁. I have shown a single three electrode tube used in the circuit of Fig. 2, but it will be understood that my invention does not require any specific type of tube as it functions equally well whatever type of amplifying tube may be used.

The input circuit of tube T₁ and the input circuit of tube T₂ are both normally of the tuned type and they are so shown in Fig. 2. The values of L₁—C₁ and L₂—C₂ are chosen to give resonance at that frequency chosen for the intermediate frequency; I have supposed it to be 175 kilocycles, a value ordinarily used today. The two coils L₁ and L₂ are ordinarily fixed in the amount of their inductance, and in the degree of their magnetic coupling and I have so shown them in Fig. 2. The condenser C₁ and C₂ are ordinarily of the adjustable type so that when the set is assembled in the factory the two circuits L₁—C₁ and L₂—C₂ can be properly tuned. These two circuits are generally adjusted once for all at the factory, when the set is built.

In Fig. 3 I have shown a circuit detail of the I F A, (the amount shown inside the dotted rectangle of Fig. 2) with my improved circuit arrangement attached. In series with each of the two circuits L₁—C₁ and L₂—C₂ I have added a condenser C_a and C_b, respectively. These added condensers are suitably of a capacity much greater than the capacity of condenser C₁ and C₂. These two condensers C_a and C_b have their terminals brought to the connections of a two way switch S, so arranged that when thrown into one direction C_a is short circuited and when thrown in the other direction condenser C_b is short circuited.

The change in circuit selectivity for the two positions of the switch, when the circuit has been adjusted for proper performance, is shown by the response curves of Fig. 4. Here are shown the selectivity curves of the I F A stage of Fig. 3, for the two positions of switch S.

As will be explained later, one position of the switch S results in the two circuits being tuned to each other; for this position the response curve of the I F A stage is shown by the solid line curve A, of Fig. 4. It is supposed that the frequency for which the I F A has been built is 175 kilocycles (175 kc), and curve A shows that this frequency requires the minimum impressed signal to get the specified output.

Thus it may be seen that it requires 100 micro-volts input to give the specified output at either 170 kc or 180 kc, but it requires only about 2 micro-volts at 175 kc. At either 160 kc or 190 kc, the required input voltage is about 8,000 micro volts.

Now such a selectivity curve tends greatly to eliminate interference between two stations transmitting on nearly the same frequency and it is because of the use of tuned intermediate fre-

quency amplifiers of this kind that the superheterodyne receiver has become known as a highly selective receiver.

Such high selectivity is however not always desirable, because of the circuits' discrimination against the higher frequency audio tones carried by the modulated high frequency wave. It is many times desirable to diminish the sharpness of the resonance curve provided that gain in fidelity of reproduction of the audio frequency signal can be obtained. Many makeshift schemes have been advocated to carry out this task but they have involved great loss in sensitivity of the receiver or difficulty in manufacture and adjustment of the set.

I have found it possible to change the form of the selectivity curve from that of curve A of Fig. 4 to that of curve B of the same figure.

Furthermore, I have found it possible to bring about the change in form of the selectivity curve without appreciably sacrificing the sensitivity of the receiver, and without requiring costly construction and difficult adjustment procedure.

The average radio program involves audio frequencies up to 5000 or 6000 per second; to faithfully reproduce such a program the radio frequency amplification of the radio receiver should amplify equally well all radio frequencies within 6000 cycles of the carrier frequency. It can be seen from curve B of Fig. 4 that I have been able to bring this about; curve B shows substantially the same amplification for all frequencies between 170 kc and 180 kc per second. As stated before, the I F A has been designed for a resonant frequency of 175 kc per second.

Referring again to Fig. 3, I will explain how the desired result is obtained. In "tuning up", or adjusting the I F A in the factory, the switch S is thrown to position 1. This short circuits condenser C_b . The two condensers C_1 and C_2 , which are of the adjustable type, are now regulated for capacity to bring about tuning of the two circuits. If the two coils L_1 and L_2 have the same inductance, this tuning operation involves the equalization of the capacity of C_2 , to that of condensers C_1 and C_a in series. This means, of course, that the capacity of C_2 is adjusted to a value slightly less than that of C_1 . The exact difference between the capacity of C_1 and C_2 depends upon the ratio of the capacity of condenser C_a to that of the condenser C_1 . For the purpose of my invention, C_1 may have a capacity about 6% that of C_a . I do not limit myself to such a proportion however because it may be advisable to use a larger or smaller proportion than this under special conditions.

The coupling between coils L_1 and L_2 must be suitably chosen if a selectivity curve such as that of curve A, Fig. 4, is to be obtained. I am assuming that such a value of coupling has been chosen. The capacity of C_b is about the same as the capacity of C_a , when C_1 and C_2 are of approximately the same capacity. In case C_1 and C_2 are not approximately the same, then the capacity of C_b will not be the same as that of C_a . It will be understood, of course, that when C_1 is not equal to C_2 , the values of inductances L_2 and L_1 will correspondingly differ.

Having now adjusted the set, with switch S in contact, as above described, the selectivity curve will be about as shown by curve A of Fig. 4.

By now shifting the switch S to position 2, the selectivity curve changes in form to that of curve B of Fig. 4. This change in form of curve is brought about by the de-tuning of the two circuits

resulting from the action of switch S. Moving this from position 1 to position 2 decreases the capacity of the $L_2-C_2-C_b$ circuit and increases the capacity of the $L_1-C_1-C_a$ circuit, each of the changes in capacity being about 6%, for the 80 conditions assumed. This de-tuning results in the selectivity characteristic shown by curve B, and this results in increased fidelity of reproduction of the audio frequency signal. This increase in fidelity is accomplished with practically no 85 loss in sensitivity.

Whereas I have shown the switch S as short circuiting a condenser, in one circuit or the other, it is quite possible to short circuit a small inductance instead. This possibility is indicated in 90 the arrangement of Fig. 5, in which the two positions of switch S short circuit either coil L_a or coil L_b . These coils would normally have an inductance about 6% that of L_1 or L_2 its exact value, however, may depart appreciably from this 95 value.

In Fig. 6, I have shown a scheme in which the switch S in the closed position short circuits condenser C_b in one circuit and inductance L_a in the other circuit and in the "open" position removes the short circuit from both pieces of apparatus. The two circuits are tuned, with the switch in either position, and the resultant selectivity is that of curve A, Fig. 4. Then when the switch is thrown into its other position, the 105 natural frequency of one circuit is raised and that of the other is lowered. This condition results in the selectivity curve shown at B of Fig. 4.

Having thus described my invention, what I 110 claim is:

1. In combination with a pair of loosely coupled tuned circuits, means including auxiliary reactances for increasing the natural frequency of one circuit by a small amount and decreasing the 115 natural frequency of the other circuit by approximately the same amount.

2. In a superheterodyne receiver having an intermediate frequency amplifier using two coupled tuned circuits between successive vacuum tubes, 120 means for changing the shape of the selectivity curve, the said means including auxiliary reactances for detuning the two tuned circuits by increasing the natural frequency of one of the circuits by a small amount and decreasing the natural 125 frequency of the other circuit by approximately the same amount as the first one has been increased.

3. In a superheterodyne receiver having an intermediate frequency amplifier using two coupled tuned circuits between successive vacuum tubes, means for successively increasing the natural frequency of one of the circuits by a small amount and then decreasing the natural frequency of the other circuit by the same amount.

4. In the intermediate frequency amplifier of a superheterodyne receiver, utilizing coupled tuned circuits for interstage coupling, a switching arrangement for successively increasing the capacitive reactance of one of the tuned circuits 140 by a small amount and then decreasing the capacitive reactance of the other tuned circuit by approximately the same amount.

5. In a superheterodyne receiver having a tuned intermediate frequency amplifier, said amplifier utilizing magnetically coupled, tuned circuits between successive amplifying tubes, said tuned circuits each having a coil and two condensers connected in series, switching means for successively removing a short circuit from a con- 150

denser in one of the circuits and imposing a short circuit upon a condenser in the other circuit.

6. In a superheterodyne receiver, a tuned intermediate frequency amplifier employing two coupled tunable circuits, auxiliary reactances in the said coupled circuits and a single control switch for increasing the natural frequency of one of the circuits by a given amount, and decreasing the natural frequency of the other cir-

intermediate frequency amplifier, said amplifier using coupled tunable circuits, a single control switching arrangement which serves practically to instantaneously change the electrical characteristics of the two circuits so that the tuned frequency of one circuit is increased by a given amount and the tuned frequency of the other circuit is lowered by approximately the same amount.

10 cuit by approximately the same amount.

7. In a superheterodyne receiver having a tuned
